UNITED STATES PATENT OFFICE.

WILTON J. WILLIAMS, OF CHICAGO, ILLINOIS.

PULVERIZER.

939,778.

Specification of Letters Patent. Patented Nov. 9, 1909.

Application filed February 16, 1909. Serial No. 473,220.

To all whom it may concern:

Be it known that I, MILTON J. WILLIAMS, a citizen of the United States, residing at Chicago, Illinois, have invented a certain new and useful improvement in Pulverizers, of which the following is a full, clear, and exact description, such as will enable others skilled in the art to which it appertains to make and use the same, reference being had to the accompanying drawings, forming part of this specification, in which—

Figure 1 is a vertical sectional view through a pulverizer constructed according to my improvement; Fig. 2 is a horizontal, fragmentary sectional view through the same.

This invention relates to a new and useful improvement in pulverizers of that type commercially known as the "Williams mills", characterized by the pivoted revolving hammers which act upon the material as it enters the machine at the hopper or feed end thereof, crushing said material as it rests upon the bottom of the hopper, or breaker plate, as it is sometimes called, the material being further disintegrated or crushed by the hammers acting thereon as the material is carried over the cage or grinding surface. The crushed material falls through the openings in the cage or grinding surface into a suitable receptacle located beneath the machine. The hammers or beaters which revolve about the shaft, while made of a material whose resistance to wear is its essential quality, will, in time, wear away at their striking ends, and the farther these striking ends are removed from the breaker plate and grinding surface, the less becomes the capacity of the machine.

It is the purpose of my present invention to provide means whereby these revolving hammers or beaters may be adjusted outwardly to take up this wear (or inwardly, if occasion requires, as when a new cage is introduced to replace a worn one), said means consisting of a longitudinally movable frame having inclined rods on which are pivotally mounted the hammers or beaters, spaced apart by suitable spacing rings and confined between disks having radial slots through which said inclined rods pass, whereby, when said rods are moved longitudinally, the hammers are adjusted inwardly or outwardly, depending upon the direction of movement of the rods.

In the drawings, 1 indicates the casing, 2 the breaker plate, 3 the grinding surface or cage, and 4 the cover of the machine, which may or may not be hung, as desired. 60

5 indicates a shaft mounted in a casing on which are fixedly mounted disks 6 having radially disposed slots 7.

8 and 9 are disks movably mounted on the shaft 5, and 10 are inclined rods supported 65 by said disks 8 and 9, said rods passing through the radial openings in the disks 6.

11 are spacing rings arranged on the rods between the disks 6. 12 are hammers pivotally mounted on the rods between said 70 disks 6 and spaced apart by said spacing rings.

13 is a disk fixed on shaft 5 and having openings through which pass threaded rods 14 from the disk 8, said threaded rods having nuts on each side of the disk 14, whereby the disks carrying the inclined rods may be adjusted longitudinally the shaft. 75

In operation, the disks 8 and 9 are so adjusted that the inclined rods lie in the inner 80 ends of the slot 7. As the hammers wear, the inclined rods are adjusted longitudinally the shaft so as to effect an outward movement of the hammers to take up wear. The hammers can also be adjusted inwardly by 85 moving the rods in the opposite direction.

I am aware that minor changes in the construction, arrangement and combination of the several parts of my device can be made and substituted for those herein shown 90 and described without in the least departing from the nature and principle of my invention.

In using the expression "disks" in the foregoing specification and in the following 95 claims, I wish to be understood as not confining myself to circular disks, as the parts which perform the functions of the supporting disks described and claimed can be in the shape of spider-arms, or other arms, 100 metal being cut away at various places where it is not needed, to lighten the machine.

Having thus described my invention, what I claim is:

1. In a pulverizer, a casing, a shaft mounted for rotation therein, disks fixed on said shaft, disks arranged to slide on said shaft, inclined rods carried by the sliding disks, which inclined rods pass through the fixed disks, and revolving hammers pivotally 110 mounted on said rods. 105

2. In a pulverizer, the combination with,

- a casing, a shaft mounted in said casing, disks fixed to said shaft and provided with radial slots, inclined rods passing through said slots, revolving hammers pivotally mounted on said inclined rods between the disks, adjusting means on the shaft and connected to the ends of the rods for moving the same through the radial slots and spacing rings between said hammers.
- 10 3. In a pulverizer, the combination with a casing, a shaft mounted in said casing, disks fixed to said shaft and provided with radial slots, inclined rods passing through said slots, sliding disks mounted on the shaft for supporting said rods, means located on the shaft and connected to one of the sliding disks for moving both of said disks upon the shaft, revolving hammers pivotally mounted on the rods between the fixed disks, and
- 15 20 means for locking said sliding disks and their carried inclined rods in longitudinally adjusted positions.
4. In a pulverizer, a casing, a shaft mounted for rotation therein, disks fixed on said shaft, disks arranged to slide on said shaft, inclined rods carried by the sliding disks, which inclined rods pass through the fixed disks, revolving hammers pivotally mounted on said rods, and spacing rings arranged between the hammers.
- 25 30
5. In a pulverizer, a casing, a shaft mounted for rotation therein, an adjustable frame mounted on the shaft, which frame comprises disks and inclined rods, a series of revolving hammers pivotally mounted and spaced apart upon the inclined rods, and means carried by the shaft whereby the hammers are held to move radially with respect to the shaft when the frame is adjusted upon said shaft.
- 40 6. In a pulverizer, a casing, a shaft mounted for rotation therein, a pair of disks fixed on the shaft and provided with radial slots, inclined rods passing through said slots, sliding disks mounted on the shaft and engaging the ends of the inclined rods, revolving hammers pivotally mounted on the rods between the fixed disks, spacing rings carried by the rods between the hammers, means whereby the sliding disks are shifted upon the shaft, and means whereby the rod-shifting means is locked after movement.
- 45 50

In testimony whereof I hereunto affix my signature in the presence of two witnesses, this 8th day of February, 1909.

MILTON J. WILLIAMS.
